UNITED STATES PATENT OFFICE.

GEORGE HAYES, OF NEW YORK, N. Y.

WHEEL FOR BICYCLES.

SPECIFICATION forming part of Letters Patent No. 610,743, dated September 13, 1898.

Application filed July 31, 1897. Serial No. 646,681. (No model.)

To all whom it may concern:

Be it known that I, GEORGE HAYES, a citizen of the United States, and a resident of the city, county, and State of New York, have 5 invented a new and useful Improvement in Wheels for Bicycles and other Vehicles, of which the following is a specification.

My improvement relates to the center portion of the wheel, and has for its object the 10 securing of elasticity and resiliency at that point instead of at the rim, thereby enabling pneumatic tires to be dispensed with; and my improvement consists in constructing the wheel-center with an axle-hub formed substantially as usual and disposed at a suitable 15 distance therefrom, an encircling spoke-nave, the two connected by certain springs, each of which is formed with an eccentric coil toward and at one end, while the other end ex- 20 tends more or less straight or tangentially thereto, the two ends being secured one to the axle-hub and the other to the spoke-nave.

It further consists of such devices and combinations of devices as hereinafter more fully 25 described and pointed out, reference being had to the accompanying drawings, in which—

Figure 1 is an edgewise view of one of the 30 springs used in the central part of the wheel. Fig. 2 is a cross-section of the axle-hub, showing inside face of one of the hub-flanges, inside face of one of the cheeks of the spoke-nave, and set of springs connecting resiliently the axle-hub and spoke-nave, with cross-rods used as braces and means for securing the 35 springs. Fig. 3 is a sectional view of the wheel-center on line *w x* of Fig. 2. A dotted line *y z* in this figure gives the section-plane of Fig. 2. Fig. 4 is an edgewise view of a spring analogous to that of Fig. 1, but in two 40 parts, terminals overlapping. Fig. 5 is a view of the hub-center similar to that of Fig. 2, but with springs reversed and in greater number. Figs. 6 and 7 are edgewise views of springs, which illustrate modifications or 45 variations permissible in form and arrangement. Fig. 8 is a view of the hub-center analogous to Figs. 2 and 5, illustrating a modification in arrangement of springs.

On the drawings, A indicates the springs 50 used in the wheel-center and which are the distinctive feature of this invention. They may be made of any shape in cross-section,

but preferably flat. They also may be used in any desired number and of any suitable width and thickness, also of any suitable material. They also may be made of one piece, as in Fig. 1, or in two parts, as in Fig. 4, or each half may be used singly. The springs are formed as eccentric coils, each coil with tangential extension.

B indicates the axle-hub. This may be of any desired style, but preferably such as usual for bicycles, each being supplied with flanges *B'*, forming part of the hub, or threaded or otherwise secured thereto.

C indicates the cheeks or end disks of the spoke-nave, which is separate and distinct from the axle-hub. The cheeks are formed as rings or disks with hollow center and encircle the axle-hub. The two cheeks are held at the proper distance apart by cross-rods *C'* or pillars, which also serve as braces. The interior ends of the spokes of the wheel are secured to the spoke-nave near the peripheral edge of the cheeks.

At D are arranged cross-rods or pillars extending between and secured to the flanges *B'* of the axle-hub. The springs have their terminals inside the coils secured to the cross-rods *D* of the axle-hub when used analogous to arrangement of Figs. 1, 2, and 3, or secured to cross-rods *C'*, while at another point or terminal they are secured to a cross-rod *C'* of the spoke-nave, and when used analogous to arrangement of Fig. 5 their securing-points are reversed.

The action sought by the use of springs of the character and arrangement herein described and shown in the drawings is a combination of vibratory and oscillatory motion, cushioning between axle-hub and spoke-nave with quick resiliency as against pressure or shock.

In Fig. 3 two sets of the springs are used, one at each end of the hub; but dotted lines at E 95 serve to show how one set of the springs may be used, their width taking up nearly the entire width between the hub-flanges. The wheel-center may be inclosed and the springs completely secured against dust, dirt, &c., if 100 desired.

At G a reinforcement is shown. It is of spring metal and intended to ease the motion in case of excessive shock. Other reinforce-

ments may be added, as leaves applied to the springs, after the usual manner against either face of the metal, wherever desirable, to obviate risk of breakage. When several sets of 5 springs are used to one hub, they may be arranged to break joints somewhat after the manner shown in Fig. 8. When round metal, as wire, is used for the springs and they are formed double, a coil, as shown in Fig. 7 at H, 10 is formed therein. The springs can be single, as one-half of Fig. 4, and joined together as there shown or without joining, as desired. The springs may also be made each with two coils after the manner shown in Fig. 6, and 15 two springs may be joined after the manner illustrated in said figure.

What I claim as new, and desire to secure by Letters Patent, is—

1. A wheel for bicycles and other vehicles 20 formed with a central axle-hub, having a set of eccentrically-coiled springs arranged at intervals in radiating lines therefrom, and resiliently connecting it with an encircling spoke-nave with which the interior ends of 25 rigid spokes engage, essentially as set forth.
2. A wheel for bicycles and other vehicles, having a set of binary springs, each formed with two eccentric coils as termini and connecting the axle-hub resiliently with a special 30 spoke-nave encircling it, and forming the center of a system of rigid spokes extending therefrom to the rim of the wheel, essentially as set forth.

3. In a wheel for bicycles and other vehicles, 35 between its axle-hub and an encircling spoke-nave, double sets of binary springs, each of which is formed with ends coiled eccentrically, and its midway web folded, essentially as set forth.

4. A wheel for bicycles and other vehicles, 40 having an axle-hub resiliently suspended within an encircling spoke-nave, by a system of binary springs eccentrically coiled toward each end of its web, secured to a spindle of the spoke-nave at the center of each coil, and 45 each engaging by a midway bend or fold with a spindle securing it to the axle-hub, essentially as set forth.

5. In a wheel for bicycles and other vehicles, 50 the combination consisting of—first; an axle-hub formed with a flange at each end, between which extend spindles parallel to the axle-hub, arranged at intervals around the same—second; a spoke-nave formed as two cheeks or disks, encircling the axle-hub and 55 united by cross-rods or spindles at intervals, and—third; double sets of binary springs, each having eccentrically-coiled ends engaging with spindles of the spoke-nave, and each formed with a U-shaped midway bend, 60 engaging with a spindle of the axle-hub, essentially as set forth.

GEO. HAYES.
